UNITED STATES PATENT OFFICE

SAMUEL P. BUSH, OF COLUMBUS, OHIO, ASSIGNOR TO THE BUCKEYE STEEL CASTINGS COMPANY, OF COLUMBUS, OHIO

CAR TRUCK CONSTRUCTION

Application filed January 4, 1927. Serial No. 158,950.

This invention relates to car truck construction and its primary object is to attain large spring capacity without widening the bolster or the bolster opening. Another object is to provide effectual means for locking the bolster to the side frame without employing outside bolster stops, and equalizing the load on the springs while facilitating disassembling of the truck to effect wheel changes, or for other purposes. These stated objects, and other objects which will appear incidentally in the course of the following description, are attained in such a structure as is illustrated in the accompanying drawings, and the invention resides in certain novel features which will be particularly pointed out in the appended claims.

In the drawings, Figure 1 is a side elevation of a car truck embodying the present invention,

Figure 2 is an enlarged horizontal section on the line 2—2 of Fig. 1,

Figure 3 is a view showing the side frame in transverse section and the bolster and associated parts in elevation,

Figure 4 is a section on the line 4—4 of Fig. 3,

Figure 5 is a section on the line 5—5 of Fig. 4 with some parts in elevation and some parts broken away,

Figure 6 is a detail plan view of the yoke or spring cap,

Figure 7 is a view similar to Fig. 2 and showing a different spring arrangement,

Figure 8 is a view in side elevation showing the bolster construction,

Figure 9 is a plan view of the bolster structure, and

Figure 10 is a view of an outer end of the bolster.

The side frame of the car truck comprises an upper compression member 1, a lower tension member 2, and columns 3 integrally connecting the compression and tension members and defining a bolster-receiving opening. The lower portion of the columns are nearer together than their upper portions, as shown in Fig. 1, and spring seats 4 are formed near the bases of the columns over the lower tension member of the side frame, the end of

the spring plank 5 being received between the lower portions of the columns and resting upon the tension member and filling the space between the spring seats 4. The end of the spring plank extends somewhat beyond the outer side of the side frame, as shown in Fig. 3, and upon the side frame are provided brackets or shelves 30 to support the parts of the springs which project over the sides of the spring plank. It will be noted that the brackets are provided on both sides of the side frame and at both sides of the spring plank so that they also guide the spring plank when assembling the truck, and also aid in resisting lateral stresses thereon. The central webs of the columns may be made of any suitable form, and are preferably made concave or semi-cylindrical in form, as shown in Figs. 2 and 7, and from the side edges of the columns, arms 6 and 7 project respectively inward and outward to abut and guide the bolster 8, the end of which extends through the upper part of the opening between the columns. Springs 9 of the usual form are disposed below the bolster, and it will be noted that there is a spring mounted on each spring seat 4 and partly housed by the corresponding column while other springs may rest partly on the brackets 30 and partly on the spring plank, the arrangement accommodating a large group of springs. In order that the full benefit of the large group of springs may be obtained in supporting the bolster, a yoke or cap 10 is provided between the springs and the bolster, said yoke or cap consisting of a plate having ends 11 constructed to project within the upright lines of the columns. The side edges of the yoke may be straight and parallel through their entire length but they are shown in Fig. 6 as parallel in their middle portions and converging from the middle portions toward their semi-circular ends, this form affording a more extended support for the bolster while maintaining the ends of the yoke housed in the respective columns. On the basal chords of the semi-circular ends, upright members 12 rise from the plate or body of the yoke to abut the sides of the bolster, as shown in Figure 4, the bolster being provided with

abutments or overhanging lips or flanges 13 to rest upon the upper edges of the uprights 12, and bracing ribs 14 being formed integral with the outer sides of the walls 12 and the 5 end portions of the plate. The bolster is preferably formed with a transverse groove 15 in its under side to receive the plate or body of the yoke, and it will now be seen that the yoke is interlocked with the bolster and 10 with the side frame through the columns thereof so that displacement of the bolster relative to the side frame is prevented. Although I have shown the groove construction in the underside of the bolster, it is ob- 15 vious that other means to serve the same purpose may be employed. It is also to be noted that the outer ends of the lips or flanges 13 form stops to abut the inner edges of the arms 7 on the columns and that inner stop lugs 16 are formed on the sides of the bolster to abut the inner edges of the arms 6, while the bolster is reduced in width from and outwardly beyond the vertical plane of the inner side of the yoke. A vertical stop shoulder 17 20 is thus produced on the bolster to abut the inner edge of the upright 12 while the outer edge wall abuts the edge of the arm 7. The two side frames of the car truck are thus effectually held in spaced relation without any 25 outside stops on the bolster.

In Fig. 2, I have shown an arrangement of six springs and it will be noted that four springs are arranged in the usual four-spring group formation and that they bear partly 30 against the yoke and partly against the bolster while the end springs bear against the ends of the yoke, thus getting the advantages of a six-spring group while the bolster need not be any wider than is ordinarily the case 35 with a four-spring group.

It will be observed that the group of springs, as an entirety, extends in the direction of the length of the side frame with the 40 end springs projecting partly within the columns and resting on the spring seats 4 and the intermediate springs arranged in rectangular relation. The corners of the rectangle defined by the intermediate springs project over the sides of the spring plank and the 45 portions of the springs which thus project are supported by the brackets 30. It is also to be noted that the overhanging lips or flanges 13 on the bolster, by bearing on the upright members of the yoke, transmit a proportional 50 part of the load to the latter and through said members to the end springs which have their axes disposed approximately in the vertical planes of said upright members.

In Fig. 7, I have shown a group of five 55 springs arranged in cruciform relation, one spring being disposed at the center of the group and between the springs which project within the upright lines of the columns so that three springs bear upwardly against the 60 yoke and two springs bear directly against

the bolster, one at each side of the yoke. The bolster in this form of the invention may be narrower than in the first-described form but is, otherwise, the same, except that it is somewhat elongated, as at 18, to accommodate the 70 outermost spring, the spring plank, of course, being likewise extended.

With my improvements, when wheel changes are necessary or, for any other reason, it is desired to disassemble the truck the bolster is jacked up so that the springs which are outside of the longitudinal center line of the frame may be removed, and so that suitable blocks may be placed between the bolster and the spring plank to hold the bolster above 80 the interlocking elements of the yoke. Then, if the spring plank together with remaining bolster springs, yoke and bolster, superposed on the spring plank, be jacked up so as to be freed from the side frame, the interengaging 85 elements at the journal boxes having been released, the side frame, yoke and springs within the columns may be withdrawn laterally as one unit leaving the spring plank, inside bolster springs and bolster in their 90 proper relation and not materially disturbed. A reverse procedure will, of course, quickly and easily reassemble the truck.

Having fully described my invention what I claim as new and desire to secure by Letters Patent, is:—

1. In a car truck, the combination of a side frame having columns and a bolster opening between the columns, a group of springs carried by the side frame, some springs projecting within the upright lines of the columns and some springs being disposed in the bolster opening, a yoke resting on a portion of the springs and engaged in the columns, and a bolster having an end resting partly on the 100 springs and partly on the yoke.

2. In a car truck, the combination of a side frame having columns and a bolster opening between the columns, a group of springs carried by the side frame, some springs projecting within the upright lines of the columns and some springs being disposed in the bolster opening, a yoke resting on a portion of the springs and engaged in the 110 columns, and a bolster having an end resting partly on the springs and partly on the yoke and interlocked therewith.

3. In a car truck, the combination of a side frame having columns and a bolster opening between the columns, a group of springs carried by the side frame, some projecting within the upright lines of the columns, a yoke above the springs, and a bolster having an end engaged in the bolster opening of the side frame and resting partly on the yoke direct 120 and partly on the springs, the ends of the yoke engaging the columns of the side frame and the bolster being provided in its under side with interlocking means whereby the yoke will lock the bolster to the side frame.

4. In a car truck, the combination of a side frame, springs carried by the side frame, a spring seat member above the springs and engaged with the side frame, portions of certain of said springs bearing at their upper ends against said member, and a bolster resting partly on said member and partly on certain of the springs and interlocking with said member, the bolster being provided with stop means abutting the side frame. 70
5. In a car truck, a side frame having columns and a bolster opening between the columns, bolster guiding arms projecting laterally from the columns, springs carried by the side frame, a yoke extending over a portion of the springs and having its ends engaged with the columns of the side frame and arranged to abut the inner ends of the outer bolster-guiding arms on the columns, and a bolster having an end resting partly on the springs and partly on the yoke and interlocked with the latter, the bolster being provided on its sides with stops arranged to abut the inner bolster-guiding arms. 75
10. In a car truck, a side frame having an upper member, a lower member and columns connecting said members, spring seats near the bases of the columns over the lower member of the side frame, brackets on the side frame adjacent the inner edges of the spring seats, a spring plank resting on the lower member of the side frame between said brackets and the lower portions of the columns, a group of springs supported by the spring plank, the spring seats and said brackets, and a bolster supported by the springs. 80
15. In a car truck, a bolster having its end portion reduced in width relative to its intermediate portion and provided near its end with overhanging lips or abutments and provided with stop shoulders on its sides at the inner ends of said lips and with other stop shoulders spaced inwardly from the first-mentioned shoulders. 85
20. In a car truck, a yoke arranged between the bolster and the springs and consisting of a plate having end portions adapted to engage within the upright lines of the columns of the truck side frame and upright members spaced inwardly from the extremities of the end portions. 90
25. In a car truck, the combination of a side frame, springs carried by the side frame, a spring seat member above the springs and engaged with said frame, said member constituting a bearing for portions of certain of the springs, and a bolster resting partly on certain of the springs and partly on said member and interlocked with the latter, the bolster being provided with stop means abutting the side frame, and other stops abutting the ends of said spring seat member. 95
30. In a car truck the combination of a side frame having columns and a bolster opening between the columns, a group of springs carried by the side frame, some springs projecting within the upright lines of the columns and some springs being disposed in the bolster opening, a yoke above the springs and engaged in the columns, a bolster interlocked with the yoke, the bolster having abutments or flanges on its sides overhanging the upright ends of the yoke whereby to transmit part of the load to the ends of the yoke and the springs projecting within the columns. 100
35. In a car truck, a yoke to fit between the bolster and the springs and consisting of a plate having end portions projecting within the upright lines of the columns, seated within and supporting in part the sides of the bolster and adapted to provide bearings for the springs. 105
40. In a car truck, the combination of a side frame having columns and a bolster opening between the columns, a group of springs carried by the side frame, some springs projecting within the upright lines of the columns and some springs being disposed in the bolster opening, a yoke above the springs and engaged in the columns, a bolster having an end resting partly on the yoke and partly on the springs and interlocked with the yoke, the bolster having abutments or flanges on its sides overhanging the upright ends of the yoke whereby to transmit part of the load to the ends of the yoke and the springs projecting within the columns. 110
45. In a car truck, a yoke to fit between the bolster and the springs and consisting of a plate having end portions projecting within the upright lines of the columns, seated within and supporting in part the sides of the bolster and adapted to provide bearings for the springs. 115
50. In a car truck, the combination of a side frame having columns and a bolster opening between the columns, a group of springs carried by the side frame, some springs projecting within the upright lines of the columns and some springs being disposed in the bolster opening, a yoke above the springs and engaged in the columns, a bolster having an end resting partly on the yoke and partly on the springs and interlocked with the yoke, the bolster having abutments or flanges on its sides overhanging the upright ends of the yoke whereby to transmit part of the load to the ends of the yoke and the springs projecting within the columns. 120
55. In a car truck, the combination of a side frame having columns and a bolster opening between the columns, a group of springs carried by the side frame, some springs projecting within the upright lines of the columns and some springs being disposed in the bolster opening, a yoke above the springs and engaged in the columns, a bolster having an end resting partly on the yoke and partly on the springs and interlocked with the yoke, the bolster having abutments or flanges on its sides overhanging the upright ends of the yoke whereby to transmit part of the load to the ends of the yoke and the springs projecting within the columns. 125
60. In a car truck, the combination of a side frame having columns and a bolster opening between the columns, a group of springs carried by the side frame, some springs projecting within the upright lines of the columns and some springs being disposed in the bolster opening, a yoke above the springs and engaged in the columns, a bolster having an end resting partly on the yoke and partly on the springs and interlocked with the yoke, the bolster having abutments or flanges on its sides overhanging the upright ends of the yoke whereby to transmit part of the load to the ends of the yoke and the springs projecting within the columns. 130

from the lower spring seats upwardly and above the springs and partially housing certain of said springs, and an upper spring seat member intermediate the springs and bolster and entering the recessed columns.

5 17. In a car truck, the combination of a side frame comprising a compression member and a tension member having oblique portions, recessed columns connecting said compression and tension members and defining a bolster opening, a bolster entering said opening, spring seats at the lower ends of the recessed columns and above the oblique portions of the tension member, means affording 10 other spring seats between the first mentioned spring seats and on the same horizontal plane therewith, and springs between said spring seats and the bolster, certain of said springs being partially housed from end to end by said recessed columns.

15 18. In a car truck, the combination of a side frame comprising compression and tension members, columns connecting said compression and tension members and defining a bolster opening, spring seats at the lower ends of said columns, a bolster entering said bolster opening between the columns, springs under the bolster and resting upon said seats, each of said columns having a contour defined by a channeled cross section extending 20 from said spring seats upwardly and above said springs, said springs being partially housed from end to end by said columns.

25 19. In a car truck, the combination of a side frame comprising compression and tension members, columns connecting said compression and tension members and defining a bolster opening, each of said columns having a contour defined by a channeled cross section, a bolster entering the bolster opening, said columns provided with parts to 30 provide bearing surfaces for the bolster, and springs under the bolster and partially housed from end to end by said columns.

45 46. In testimony whereof, I have signed this specification.

SAMUEL P. BUSH.
